UNITED STATES PATENT OFFICE.

ARTHUR H. WOODWARD, OF CHICAGO, ILLINOIS, ASSIGNOR TO THE INTERNATIONAL REGISTER CO., OF CHICAGO, ILLINOIS, A CORPORATION OF ILLINOIS.

LOOSE-LEAF BINDER.

Application filed April 25, 1924. Serial No. 708,848.

My invention relates to loose-leaf binders, and more particularly to binders employing binding posts adapted to pass through holes in the loose leaves.

5 The object of the invention is a generally improved construction with a view to simplicity and sturdiness and to improving upon the means for locking the free ends of the binder posts after the book leaves are 10 in position on these posts.

Referring to the accompanying drawings in which I have illustrated a preferred embodiment of my invention:

Figure 1 is a sectional view on a plane 15 parallel with the pages through a loose-leaf book embodying my improved loose-leaf binder;

Fig. 2 is a plan sectional view taken through the plane of one of the binding 20 posts;

Fig. 3 is a fragmentary sectional view illustrating the hinged mounting of the post locking leaf and the arrangement of the spring detent;

25 Fig. 4 is a transverse sectional view through the binder, illustrating the hinge connections between the back plate and the post supporting leaf and the post locking leaf;

30 Figs. 5 and 6 are vertical sectional views taken through the binder and looking in opposite directions to show the hinge mounting of each leaf of the device;

35 Figs. 7 and 8 are detail sectional views showing the function of the bead or flange struck out around the outer end of each locking slot;

40 Fig. 9 is a perspective view of the binder mounted in the book, showing the binder opened up with the two leaves folded back; and

Fig. 10 is a plan view of the same.

The binder unit constituting the present invention is designated by numeral 12 in 45 its entirety, this binder unit being illustrated separate from the loose-leaf book in Fig. 4. This unit comprises a back plate 14, which is preferably arched to accord with the shape of the book back, as shown in Fig. 10. Hinged to the lateral edges of this back plate 14 are a post supporting side leaf 15 and a post locking side leaf 16. Suitably secured to the leaf 15 are two (or

more) binder posts 17 which are adapted to pass through holes in the book pages. 55

The binder unit 12 is mounted in the back of the loose leaf book 18 in any preferred manner, which will be obvious to those skilled in the bookbinding art. The back plate 14 is preferably secured across its 60 entire rear surface to the back 19 of the book cover, the side covers or leaves 21—21 having hinged connections with the book back 19 adjacent the lateral edges of the arched back plate 14. This metallic back plate 14 65 thus reinforces the entire back of the book.

Referring again to the construction of the binder unit 12, it will be observed from Figures 4, 6 and 9 that the post supporting leaf 15 is punched out to leave rectangular 70 openings 23 adjacent its upper and lower ends. Likewise, the post locking leaf 16 is punched out with long narrow slots 24 adjacent its upper and lower ends. In punching out the back plate 14 tongues 25 75 are left extending from both edges of the plate for engaging in these openings or slots 23 and 24. As shown in Fig. 4, these tongues are looped in through these openings or slots from the outside of the leaves 80 15 and 16 and are then curled backwardly on the inner sides of these leaves. It will be noted that the metal is cut away from the edge of the back plate 14 on each side of each tongue 25, as indicated at 26, so as 85 to permit the tongues to be curled inwardly for forming the hinge connection short of the lateral edge of the back plate 14. One tongue 25' for hinging one end of the post locking leaf 16 is adapted to have a detent 90 spring 27 play against its inner edge, and to accommodate this detent spring the adjacent edge of the arched back plate 14 is cut out along a greater length, as indicated at 26'. For facility of assembly, the other 95 edge of the back plate is cut out to this greater depth 26', as indicated of the lower tongue 25 in Fig. 6. Thus, irrespective of which edge of the back plate the post locking leaf 16 is hinged to, the detent spring 100 27 will find clearance for the endwise sliding motion of this locking leaf.

The binder posts 17 are rigidly mounted in the post supporting leaf 15 in any suitable manner, such as by having reduced ends 105 which are passed through openings in the

leaf 15 and are then headed or riveted over, as indicated at 28. The free ends of the posts 17 are formed with annular grooves 29, leaving outer locking heads 31 which are less in diameter than the posts themselves.

The other leaf 16 has locking slots 32 of keyhole form punched out substantially opposite the ends of the binder posts 17. 10 The enlarged ends of the locking slots 32 will permit the locking heads 31 on the ends of the binder posts to pass freely through to the other side of the locking leaf or strip, but are too small to permit the post itself 15 to enter them, insuring register with the groove, this leaf or strip and the binding post being then relatively moved to bring the narrowed ends of the slots 32 into the grooves 29.

20 This shifting movement for locking and unlocking the binder posts 17 may be accomplished by hinging the post supporting leaf 15 for shifting movement, or by hinging the post locking leaf 16 for shifting movement. 25 The latter practice is preferable, because the shifting of the post locking leaf 16 does not involve any shifting of the book pages, which may be tightly compressed against the back of the book. As shown in Fig. 5, 30 the relatively narrow slots 24 are elongated sufficiently to permit the leaf 15 to be slid endwise sufficiently to clear the locking heads 31 of the reduced ends of the locking slots 32. After the book pages 20 (Fig. 2) have 35 been slipped over the binder posts 17 the two leaves 15 and 16 are swung together and the latter leaf 16 is shifted upwardly to permit the insertion of the ends of the binder posts into the locking slots 32, after which the leaf 40 16 is shifted lengthwise into its locking position illustrated in Fig. 5. The locking leaf 16 is normally retained in this position by the detent spring 27. As shown in Fig. 3, this is a flat leaf spring secured at its inner 45 end to the outer wall of the locking leaf 16 by rivets 34. The spring extends substantially flat along the hinged leaf 16 to the inner end of the hinge tongue 25', where it is formed with an outwardly curved hump 35. 50 This hump 35 snaps down over the inner edge of the tongue 25' when the locking leaf 16 is shifted to locking position, and thereby operates to retain this leaf in this locking position. When the leaf is shifted endwise 55 to unlocking position the spring 27 is cammed up over the top of the tongue 25'. The adjacent end of the locking leaf 16 may be formed with an outwardly turned lip 36 for facilitating of grasping the end of the leaf in order to pull it longitudinally to effect the unlocking of the binder posts 17.

60 Referring to Fig. 8, it will be noted that the end of each locking slot 32 opposite the reduced end is formed with an outwardly punched flange 37 struck out of the metal in

the operation of punching out the locking slot. This flange or shoulder lies in the plane of the locking head 31 on each binding post 17, so that when the locking leaf 16 is pulled endwise these blocking shoulders 37 70 will engage the locking heads 31 and prevent the grooves 29 from relocking themselves over the opposite ends of the locking slots 32. Thus, by mere endwise pulling of the leaf 16 the locking heads 31 and the enlarged 75 ends of the locking slots 32 will automatically center for unlocking separation.

I do not intend to be limited to the particular details herein shown and described except as they are defined in the appended 80 claims.

I claim:

1. In a loose-leaf binder, the combination of a back member, side members attached to said back member, binder posts supported by one of said side members, and means for effecting locking engagement between the other side member and the free ends of said posts, said means being releasable by sliding motion of said other side member relative to said back member and the attachment of said last side member to said back member permitting sliding motion of said side member relative thereto.

2. In a loose-leaf binder, the combination of a back member, binder posts supported by said back member, and a locking side member adapted to have hinged movement relative to said back member, said locking member also having shifting movement relative to said back member for engaging said binder posts.

3. In a loose-leaf binder, the combination of a back member, a pair of side members hinged thereto, binder posts supported by one of said side members, the other side member being adapted to make locking connection with the free ends of said posts and having translational motion relative to said back member for releasing said posts.

4. In a loose-leaf binder, the combination of a back plate, a pair of binder posts, a post-supporting leaf on which said binder posts are mounted, said leaf having hinged connection to said back plate adjacent one edge thereof, a post-locking leaf adapted to effect a locking engagement with the free ends of said posts, and hinge means between said post-locking leaf and said back plate for permitting shifting movement of said locking plate to unlock said posts.

5. In a loose-leaf binder, the combination of a back plate, a pair of binder posts, a post-supporting leaf to which said posts are attached, a hinge connection between said supporting leaf and said back plate, a post-locking leaf having locking slots adapted to engage with the free ends of said posts, and a hinge connection between said locking leaf and said back plate permitting relative 120 125 130

shifting movement of said locking leaf to release said slots from said posts.

6. In a loose-leaf binder, the combination of a back member, a binder post carried by said back member, a locking groove in said binder post adjacent its free end, a slide member having a locking slot therein, one end of said slot being reduced for engaging

with said locking groove, and a projection at the other end of said slot for preventing said groove from locking over said other end of said slot. ¹⁰

In witness whereof, I hereunto subscribe my name this 11th day of April, 1924.

ARTHUR H. WOODWARD.
